UNITED STATES PATENT OFFICE.

JUSTUS R. KINNEY, OF ALLSTON, MASSACHUSETTS.

STRAINER.

Application filed January 18, 1923. Serial No. 613,336.

To all whom it may concern:

Be it known that I, JUSTUS R. KINNEY, a citizen of the United States of America, and a resident of Allston, in the county of Suffolk and State of Massachusetts, have invented certain new and useful Improvements in Strainers, of which the following is a specification.

This invention relates to strainers and particularly to devices of this kind in which two strainer baskets are provided, one of which is adapted to be in commission at all times while the other is being cleaned or repaired.

The main object of the invention is to provide, in an apparatus of this class, means whereby the liquid will have a free passage from the inlet pipes to either strainer basket through a lower chamber, which chamber and basket may be readily cleaned out as desired, while the use of the other strainer basket may be continued.

The invention consists of a casing having two compartments, in each of which a strainer basket is positioned, and beneath each of which is a chamber communicating with the outer end of the strainer compartment, the inner ends of both compartments and chambers communicating with a valve member which is adapted to be rotated to permit the liquid to flow from a common inlet through either strainer basket to a common outlet.

The invention further consists of certain novel features of construction and arrangement of parts which will be understood readily by reference to the description of the drawings and to the claims to be hereinafter given.

For the purpose of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a horizontal section of a twin strainer embodying the principles of the present invention.

Figure 2 represents a vertical section of the same on line 2, 2 on Fig. 1, and

Figure 3 represents a side elevation of the same with the cover plates removed.

Similar characters indicate like parts throughout the several figures of the drawings.

In the drawings, 10 is a casing having therein a vertical valve chamber 11, the lower end of which communicates with an inlet opening 12 in axial alignment therewith, while an outlet opening 13 extends laterally from a point near the upper end thereof.

The casing 10 is also provided with two sets of passages communicating with the valve chamber 11, each set consisting of a horizontal chamber 14 and a compartment 15 located in the upper part of said horizontal chamber.

Each compartment 14 communicates with the valve chamber 11 by means of a port 16, and each compartment 15 communicates with said valve chamber by a port 17. The two sets of passages 14, 15 are separated from each other by a vertical wall 18. The outer end of each horizontal chamber 14 is closed by means of a cover plate 19, secured to the casing 10 by means of bolts 19^x.

The outer wall 20 of each compartment 15 is provided with a depression in which is disposed the annular member 21 supporting the outer end of the basket 22, said annular member 21 having a bale 23 formed thereon, by which the basket 22 may be removed from the compartment 15 when desired.

Each horizontal chamber 14 has a drain opening 24 in the bottom thereof, normally closed by means of a plug 25. By removing this plug 25, the horizontal chamber 14 may be drained of all liquid contained therein.

The valve chamber 11 is preferably cone-shaped as shown in Fig. 2, and has a cone-shaped plug 26 positioned therein, this plug being divided into two sections by means of the horizontal wall 27, the lower section 28 of which communicates at its lower end with the inlet opening 12. This lower section 28 has a lateral port 29 adapted to register with either port 16 leading to one of the horizontal chambers 14.

The upper section 30 of the valve plug 26 is provided with a lateral port 31 adapted to register with a port 17 communicating with one of the compartments 15. The port 31 is substantially above the port 29 so that they will simultaneously register with the ports 16, 17 of either set of passages 14, 15.

When the valve plug 26 is in the position

indicated in Fig. 1 of the drawings, the liquid will pass through the inlet opening 12 into the lower section 28 and through ports 29 and 16 into the horizontal chamber 14 and thence into the open end of the basket 22 in the compartment 15, all sediment in the liquid being caught in the screen of the basket 22, while the liquid, freed from this sediment, will pass through the closed end 10 of the basket 22 and through the ports 17 and 31 across the section 30 and through the port 32, and then from the casing through the outlet opening 13.

The port 32 is of such a width as to register with the outlet opening 13 whenever the port 31 is in register with either of the ports 17. In other words, by turning the valve plug 26 about its axis, either set of passages 14, 15 may be brought into commission, 20 while the other set is placed out of commission. When one set of passages is out of commission, the cover plate 19 of that set may be removed, thereby permitting the removal of the strainer basket 22 so that the 25 same may be thoroughly cleansed before it is again returned to its position in the compartment 15 for further use.

The upper end of the valve chamber 11 is closed by the tubular head 33 having a gland 30 34 thereon of the usual stuffing box, through which extends a stem 35 of said valve plug 26. When the valve plug 26 is moved about its axis so that the port 31 will be midway between the two ports 17, both sets of 35 passages will be cut off from the valve chamber 11.

By constructing twin strainers in the manner herein described, with the strainer basket horizontally disposed in a compartment at 40 the top of the horizontal chamber, the liquid to be strained is adapted to pass through the horizontal chamber upwardly into the open end of the strainer basket 22 and thence outwardly through the upper section of the 45 valve plug to the discharge opening.

By this construction, the full benefit of the entire screen work of the basket 22 is made possible.

It is believed that the operation and many 50 advantages of the invention will be understood readily without further description.

Having thus described my invention, I claim:

1. In a device of the class described, a 55 casing having a vertical valve chamber communicating with two sets of passages, each set consisting of a horizontal chamber and a compartment above and communicating with said chamber; a strainer basket horizontally disposed in each compartment; and a valve in the valve chamber adapted to 60 close the ports communicating with either set of passages.

2. In a device of the class described, a 65 casing having a vertical valve chamber com-

municating with two sets of passages, each set consisting of a horizontal chamber and a compartment above and communicating with said chamber; a strainer basket horizontally disposed in each compartment; and a valve in the valve chamber adapted to close the ports communicating with either set of passages, said valve being hollow and separated by a division wall into two sections, one of which communicates with the 75 inlet and the other with the outlet of said casing.

3. In a device of the class described, a casing having a vertical valve chamber communicating with two sets of passages, each 80 set consisting of a horizontal chamber and a compartment above and communicating with said chamber; a strainer basket horizontally disposed in each compartment; and a valve in the valve chamber adapted to close the 85 ports communicating with either set of passages, said valve being hollow and separated by a division into two sections, the lower of which communicates with the inlet and the other with the outlet of said casing. 90

4. In a device of the class described, a casing having a vertical cone-shaped valve chamber communicating with two sets of passages, each set consisting of a horizontal chamber and a compartment above and communicating with said chamber; a strainer basket horizontally disposed in each compartment; a valve in the valve chamber adapted to close the ports communicating with either set of passages; and means for 100 forcing said valve to its seat.

5. In a device of the class described, a casing having a vertical valve chamber communicating with two sets of passages, each set consisting of a horizontal chamber and a compartment above and communicating with said chamber; a strainer basket horizontally disposed in each compartment; a valve in the valve chamber adapted to close the ports communicating with either set of 105 passages; and means for draining said chambers.

6. In a device of the class described, a casing having a vertical valve chamber and two sets of passages, each set consisting of a horizontal chamber communicating with the lower part of said valve chamber, and a compartment in the upper part of each horizontal chamber with its outer end separated from the outer wall of said horizontal chamber, which outer wall has a large opening therein giving access to said horizontal chamber and its connecting compartment; a closing cover for said opening; a strainer basket in each compartment; and a valve in the valve chamber adapted to close the ports 120 communicating with either set of passages. 125

7. In a device of the class described, a casing having a vertical valve chamber provided with an inlet opening at the lower 130

- end thereof and an outlet opening extending laterally therefrom, said casing having two sets of passages, each set consisting of a horizontal chamber having a compartment 5 in the upper part thereof communicating at one end with said horizontal chamber and at the other end with said valve chamber, which valve chamber also has a port into said horizontal chamber; a basket horizontally disposed in each compartment with its open end adjacent the outer wall of said casing; and a rotary valve in said valve chamber having a passageway therethrough adapted to connect either horizontal chamber 10 with said inlet opening, and another passageway therethrough adapted to connect either compartment with said outlet opening.
8. In a device of the class described, a casing provided with an inlet and an outlet and having two parallel horizontal compartments; a horizontal passage beneath each compartment and communicating with one end thereof; a strainer basket horizontally disposed in each compartment; and a single vertical valve rotatable in said casing having a horizontal division wall dividing said valve into two sections, the lower of which communicates with the inlet and the upper with the outlet, said valve also having a port in its upper section adapted to communicate with the opposite end of either compartment, and a port in its lower section adapted to communicate 35 with the inner end of either passage.
9. In a device of the class described, a casing provided with a vertical valve chamber having an outlet near its upper end and an inlet near its lower end, said casing having two compartments both communicating at one end directly with said valve chamber and indirectly at the opposite end through separate passages extending beneath said compartments; a vertically disposed valve rotatable in said chamber and divided into two sections, the upper section having a port adapted to communicate with either compartment and a port adapted to communicate with said outlet, while the lower section communicates with the inlet and has a port adapted to communicate with either passage; and a strainer basket horizontally disposed in each compartment.
10. In a device of the class described, a casing provided with a vertical valve chamber having an outlet near its upper end and an inlet near its lower end, said casing having two compartments both communicating at one end directly with said valve 50 chamber and indirectly at the opposite end through separate passages extending beneath said compartments; a vertically disposed valve rotatable in said chamber and divided into two sections, the upper section having a port adapted to communicate with either compartment and a port adapted to communicate with said outlet, while the lower section communicates with the inlet and has a port adapted to communicate with either passage; and a strainer basket horizontally disposed in each compartment.
11. In a device of the class described, a casing provided with a vertical valve chamber having an outlet near its upper end and an inlet near its lower end, said casing having two compartments both communicating at one end directly with said valve chamber and indirectly at its opposite end through separate passages extending beneath said compartments; a vertically disposed valve rotatable in said chamber and divided into two sections, the upper section having a port adapted to communicate with either compartment and a single port adapted to communicate with said outlet when the first mentioned port is communicating with either compartment, while the lower section communicates with the inlet and has a port adapted to communicate with either passage; and a strainer basket horizontally disposed in each compartment.
12. In a device of the class described, a casing provided with an inlet and an outlet and having two parallel horizontal compartments; a horizontal passage beneath each compartment and communicating with one end thereof; a strainer basket horizontally disposed in each compartment and entirely removed from the bottom of said compartment; a single vertical valve rotatable in said casing and having a horizontal division wall dividing said valve into two sections, the lower of which communicates with the inlet and the upper with the outlet, said valve also having a port in its upper section adapted to communicate with the opposite end of either compartment and a port in its lower section adapted to communicate with the inner end of either passage.

Signed by me at 746 Old South Bldg., Boston, Mass., this 28th day of December, 1922.
